UNITED STATES PATENT OFFICE.

CHARLES E. HEYER, OF CHICAGO, ILLINOIS, ASSIGNOR TO BARNHART BROTHERS & SPINDLER, OF SAME PLACE.

DESIGN FOR A FONT OF PRINTING-TYPE.

SPECIFICATION forming part of Design No. 20,506, dated February 3, 1891.

Application filed October 31, 1889. Serial No. 328,846. Term of patent 14 years.

To all whom it may concern:

Be it known that I, CHARLES E. HEYER, a citizen of the United States, residing at Chicago, county of Cook, and State of Illinois, have invented and produced a new and original Design for a Font of Printing-Type, set forth in the following specification, reference being had to the accompanying typographical impressions, forming a part thereof.

10 This design comprises capitals, character &, dollar-mark, points, figures, and lower-case letters. In general it is a heavy-faced somewhat ornamental and quite condensed style of letter, approaching the general character 15 of Gothic type, being entirely without hair-lines and having very few tapering shades.

Another special characteristic of this design is exhibited in the second form of capital E, second form of capital L, and in capital J,

consisting of the lower terminals of said letters, respectively. This terminal is a very heavy relatively-short upwardly-convex crescent swell, which merges in the lower stroke of the letter and is more than a half-circle in extent, so that its terminal horn, which is sharp, points inward—that is, toward the commencement of the crescent form.

I claim—

The design for a font of printing-type herein shown and described.

In testimony whereof I have hereunto set my hand, at Chicago, Illinois, in the presence of two witnesses, this 25th day of October, A. D. 1889.

CHAS. E. HEYER.
